UNITED STATES PATENT OFFICE.

BENJAMIN F. D. MILLER, OF WOOSTER, OHIO, ASSIGNOR TO FRANK HERMAN AND C. C. ADAMS, OF WOOSTER, OHIO.

MUSIC-LEAF TURNER.

SPECIFICATION forming part of Letters Patent No. 699,548, dated May 6, 1902.

Application filed July 15, 1901. Serial No. 68,333. (No model.)

To all whom it may concern:

Be it known that I, BENJAMIN F. D. MILLER, a citizen of the United States, residing at Wooster, in the county of Wayne and State 5 of Ohio, have invented new and useful Improvements in Music-Leaf Turners, of which the following is a specification.

My invention relates to music-leaf turners; and the object of the same is to improve the 10 device for which Letters Patent No. 463,529 were granted me. The several improvements consist, first, of means for turning the frames by mechanism operated by the knees of the player; secondly, detachable means for connecting the device to the music-board, and, 15 thirdly, of detachable means for securing the frames to the back. The novel construction by which this is accomplished is fully described in this specification and claimed, and 20 illustrated in the accompanying drawings, forming a part thereof, in which—

Figure 1 is an elevation of my device. Fig. 2 is a vertical transverse section of the same. Fig. 3 is a detail perspective of the trigger 25 mechanism. Fig. 4 is an elevation of a piano with my device attached thereto. Fig. 5 is a detail fragment showing the crank-arms and sheaves. Fig. 6 is a detail perspective showing one of the spring-actuated levers. Fig. 30 7 is a detail perspective of the inclined axle.

Like numerals of reference designate like parts in the different views of the drawings.

The numeral 1 designates a music-board of an upright piano. My device is supported 35 by this music-board 1, and to supply means for attaching it thereto U-shaped brackets 4 are rigidly secured to the front face of the board 1, one near the top and the other near the bottom. The brackets 4 are each provided with two apertures 5 and 6, round and 40 square, respectively, for a purpose which will appear.

The back frame of my music-holder is designated by the numeral 7 and is, in the main, 45 of the usual construction, being formed of vertical side bars 8 and a center bar 9 and pivoted horizontal bars 10. Rubber bumpers 11 are secured to the bars 8. The center bar 9 is formed of two nesting flanged sections 9^a and 9^b, and formed integral with the rear section 9^b are two casings 10' and 11'.

Rounded lugs 12 project from the casing and are designed to fit the round apertures 5 in the brackets 4. Spring-actuated catches 13 are pivoted within the casings 10' and 11' 55 and project through apertures therein. These catches are notched at 13^a and rounded off at 13^b to adapt them to enter and engage the edges of the apertures 6 in the brackets 4. Means for operating the catches 13 to disengage them is provided and comprises a cord 14, connecting the catches 13, and a key 15, mounted on the forward side of the casing and having a shank 16 extending thereinto and bearing a hollow cross-bar 17, through 60 which the cord 14 passes. By this arrangement the catches 13 can be operated and disengaged by simply turning the key 15.

As in my former device above referred to, a series of hinged brackets or frames 18 are 70 used and pivoted to an inclined axle 19, secured to the center bar 9. The frames 18 are each provided with gravity-catches 20 and operated by arms 21, bearing beveled lugs 22 and pivoted to upturned feet 22^a on the lower 75 end of the bar 9. The arms 21 are provided with sheaves 24 integral therewith, and rigid arms 25, secured to the frame, serve as stops to limit the backward swing of the arms. Springs 23^a, surrounding the pivots, serve to 80 return the arms to their initial positions after displacement. The lugs 22 are designed to engage the frames 18 to turn them over. Cords 26 pass around the sheaves 23 and are oppositely connected to crank-arms 27 on angular shafts 28, passing through apertures 28^a 85 in the music-board 1. The shafts 28 are turned by means of lever-arms 29, having hubs 30 integral therewith and fitting over said shafts 28. The shafts 28 are inclosed in 90 housings 31 and provided with flanges 32. Stiff spiral springs surround the hubs 30 and are secured to an ear 33 and to the levers 29. The flanges 32 serve to confine the springs. The outer ends of the lever-arms 29 engage 95 slots 34, which serve to limit their movement in both directions. Cords 35^a are connected to the arms 29 and pass up and over pulleys 35, mounted on the back of the music-board, and then down through the back of the keys 100 and through the casing of the piano and are connected to levers 36, pivoted to the box of

the piano beneath the keyboard. The levers 36 are constructed to be operated by the knees of the player to pull the cords 35 to operate the lever-arms 29 to operate the arms 21 to fold over the frames 18, carrying the leaves of music.

The axle 19 is made detachable from the back for convenience in attaching leaves of music to the frames 18. This is accomplished by means of parallel guides 37, mounted on the bar 9, with an intervening space 38. Oppositely-extending tongues 39, rigid on the axle 19, are constructed to slip under the guides 37, which extend on each side of the axle, and thus securely hold the axle in place. To remove the axle, it is moved longitudinally upward, and thereby disengaged from the guides 37.

As the function and relation of each of the parts have been fully set forth, no further description of operation is deemed necessary.

I do not wish to be limited as to details of construction, as these may be modified in many particulars without departing from the spirit of my invention.

Having described my invention, what I claim as new, and wish to secure by Letters Patent, is—

1. In a music-turner the combination with a back frame having a center bar, of lugs projecting from the back of said bar, notched spring-actuated catches located adjacent to said lugs, a cord connecting said catches, and a key having a longitudinally-apertured cross-bar which is threaded on said cord, said key being constructed to be turned to tighten said cord to operate said catches, substantially as described.

2. In a music-turner, the combination with a music-board bearing apertured U-shaped brackets, of a back frame having a center bar, of lugs projecting from said center bar and constructed to fit said apertures in said brackets, of pivoted spring-actuated catches

constructed to engage apertures in said brackets, a cord connecting said catches, and a key connected to said cord and constructed to be operated to disengage said catches, substantially as described.

3. In a music-leaf turner, the combination with a music-board bearing U-shaped brackets having apertured cross-bars, of a back frame, spring-actuated notched catches mounted on said back and located to engage said apertures in said brackets, a cord connecting said catches, and means for tightening said cord to operate said catches to disengage them from said brackets, substantially as described.

4. In a music-turner, the combination with frames for supporting music and constructed to be folded over, of spring-actuated arms bearing sheaves and constructed to engage said frames, angular shafts bearing crank-arms, cords passing around said sheaves and connected to said crank-arms, spring-actuated lever-arms mounted on said angular shafts, levers arranged to be operated by the knees of the player to turn the said frames, cords connected to said lever-arms and to said knee-operated levers, substantially as described.

5. In a music-turner, the combination with a back, of parallel guides mounted on said back with an intervening space, of an axle bearing folding frames, oppositely-extending ears mounted on said axle and constructed to fit under said guides and hold the axle in place, said ears being located in substantially the same plane with said shaft, substantially as described.

In testimony whereof I have hereunto set my hand in presence of two subscribing witnesses.

BENJAMIN F. D. MILLER.
